UNITED STATES PATENT OFFICE.

JAMES WILLIAM TATUM, OF DURHAM, NORTH CAROLINA, ASSIGNOR TO DURHAM NOVELTY COMPANY, OF DURHAM, NORTH CAROLINA, A CORPORATION OF NORTH CAROLINA.

WINDOW-SHADE.

1,355,273.

Specification of Letters Patent.

Patented Oct. 12, 1920.

Application filed September 18, 1919. Serial No. 324,453.

To all whom it may concern:

Be it known that I, JAMES WM. TATUM, a citizen of the United States, residing at Durham, in the county of Durham and 5 State of North Carolina, have invented certain new and useful Improvements in Window-Shades; and I do declare the following to be a full, clear, and exact description of the invention, such as will enable others 10 skilled in the art to which it appertains to make and use the same.

This invention relates to window shades.

One object of the invention is to generally improve upon devices of this character by 15 providing shade-brackets one of which is a combined curtain-pole support and shade-roller support and also forms a guide for the cord or string which turns the shade-roller means being provided, on one of the 20 brackets, in connection with normally ineffective stops, to limit the unwinding of the shade from the shade-roller, thereby preventing the shade from being accidentally ripped from the roller.

25 Another object is to provide a device of this character which can be manufactured at a comparatively low cost, the brackets being formed of sheet metal blanks or stampings and assembled in an exceedingly convenient and easy manner.

Other objects and advantages may become apparent to persons who read the following details of description in connection with the accompanying drawings in which: 35 Figure 1 is a top plan view of my complete window shade in position on a window frame.

Fig. 2 is a front elevation of the upper portion of the window frame to which the 40 device is attached, the lower portion of the curtain being torn off, and one of the curtain-pole supports being omitted.

Fig. 3 is a left-hand view of the device, a portion being broken away for the sake 45 of showing other portions.

Fig. 4 is a horizontal sectional view along the line 4—4 of Fig. 3.

Fig. 5 is a detail view illustrating the right-hand shade bracket in connection with 50 the headed fastener and pawl which serve to limit the unwinding of the curtain.

Fig. 6 is a vertical sectional view, the section being taken along the line 6—6 of Fig. 1.

Referring to these drawings in detail in 55 which similar reference characters correspond with similar parts throughout the several views, and in which the window frame 1 is merely illustrated to show the relation of my improved window-shade 60 thereto,—

The device comprises a pair of shade brackets 2 and 3, a shade roller 4, a shade or curtain 5 on the roller, a string or cord 6, a pawl 7, and headed fasteners 8, one of 65 which co-acts with the pawl 7 for limiting the unwinding of the curtain 5 from the roller 4, as will be more fully described hereinafter.

The shade bracket 2 comprises an apertured flange 9 through which screws or other appropriate fastening means may extend for securing the bracket to the window frame. The other end of this bracket is formed with apertured flange 10, the upper 75 aperture 11 of which constitutes a guide for the string or cord 6, and the lower aperture 12 provides a seat for a curtain-pole support 13, the latter being formed with a hooked end which extends through the aperture 12 and is supported by the portion of the flange 10 below this aperture or slot. Adjacent to the middle portion of the bracket 2, or between the flanges 9 and 10, a horizontally extending slot or trunnion 85 bearing 14 is provided, and between this slot and the flange 9 a tongue or shoulder 15 is provided, its shoulder being struck up from the sheet metal of which the bracket is formed.

The bracket 3 is formed of sheet metal and has an apertured flange 9 similar to and serving the same purpose as that of the bracket 2, and the front flange 10' of the bracket 3 eliminates the aperture 11, but is 95 provided with an aperture or slot 12 for supporting a curtain-pole support 13, to coact with that of the bracket 2. The bracket 3 is formed with a headed ear 16 through which a flange 17 of the pawl 7 extends, 100 a yieldable and somewhat elastic tongue 18 being struck up from the sheet metal of which the member 7 is formed. By this construction, it will be seen that the flange 17 and its tongue 18 can be forced through 105 the aperture or slot of the ear 16, and that the tongue 18 springs outward so as to prevent disengagement of the flange 17 from the

slotted ear 16, at the same time permitting the front end of the pawl 7 to be raised and lowered, by winding the curtain 5 on the roller 4. The roller 4 is provided with 5 trunnions 19, one of which extends through the slot 14, the other being seated in a notch 20 of the curtain-bracket 3. Moreover the roller 4 is provided with a toothed wheel 21, the same being provided with any appropriate number of teeth or shoulders 22 which are adapted to be arrested and held by the shoulder or abutment 15 so as to control rotary movement of the roller. It will be seen that when the string 6 is pulled outward 10 through the aperture 11, it first pulls this end of the roller forward so that the left-hand trunnion moves forward in the slot 14, and the shoulder 22 is disengaged from the shoulder 15, and now by continuing to pull 15 the cord or string 6, the roller will be rotated so as to wind up the curtain 5, it being understood that the cord 6 is coiled around the roller 4 when the curtain is down. However, if the string 6 is permitted to ascend 20 gradually while the tooth 22 is out of engagement with the shoulder 15, and a downward pull is exerted on the curtain 5, the curtain will be lowered. In this connection, it will be understood that in thus 25 allowing the string 6 to gradually ascend, a sufficient resistance to its ascent should be employed to cause the trunnion to remain in the forward end of the slot 14, so that the tooth 22 is out of position to be engaged by the shoulder 15. Moreover, if 30 the weight of the unwound portion of the curtain 5 is sufficient, it is not necessary to exert a downward pull on the curtain, but as the cord 6 ascends gradually the weight 35 of the curtain causes the roller to rotate while the limited resistance of the string retains the tooth 22 out of engaging relation with the shoulder 15. It will be seen, therefore, that the string 6 constitutes means 40 for effecting the lowering of the curtain as well as the raising thereof.

For the purpose of providing both anchorage and a guide or limiting element of the string 6, and also providing a guide or 45 limiting element for the curtain 5, a sheet metal ring or disk 23 is snugly and securely fitted around the roller 4 so as to form in effect a radial flange on the roller, this flange or disk 23 is apertured at 24 to permit the string 6 to pass twice through this 50 aperture, and the string 6 is attached by forming a knot 25 thereon, passing the string from the left side through to the right side of the flange 23, then winding the string once around the roller 4 and 55 threading it back through the flange 23 from right to left. The string 6 is then threaded through the aperture 11 and is ready for operation, assuming that the curtain 5 has first been wound upon the roller 60

4, so that the unwinding of the curtain effects the winding of the cord or string 6 and vice-versa.

Referring now to the fasteners 8, it should be understood that these are supplemental 70 fasteners, and that the curtain 5 is secured to the roller by a means ordinarily employed, such as small tacks, etc., as indicated at 26 in Fig. 2. The headed fasteners 8, therefore, have a more important function than that of fastening or helping to fasten the curtain on the roller, viz., providing an abutment with which the pawl 7 co-acts to limit the unwinding of the shade from the roller. As indicated in Figs. 1 75 and 4, the head of the right-hand member 8 is somewhat spaced from the portion of the curtain through which it extends into the roller, and therefore, the pawl 7 engages against the shank of this member 8 and is retained in such engagement by the head of this member. The pawl 7 rests upon the curtain when the members 8 are covered by the windings of the curtain, but when the members 8 are uncovered as the inner winding 80 of the curtain begins to unwind, the pawl 7 is now in the path of the right-hand member 8 and engages therewith to stop the roller before the curtain is entirely unwound from the roller, thereby preventing the 85 curtain from being torn away from the tacks 26.

Although I have described this embodiment of my invention very specifically, it is not intended to limit this invention to 100 these exact details of construction and arrangement, but changes may be made within the scope of the inventive ideas as implied and claimed.

What I claim is my invention is:

1. The combination of a shade-roller, including a trunnion and a shoulder, a string connected to the shade roller for turning the roller, and a bracket including a bearing, a shoulder and a guiding flange, the latter extending substantially parallel to said trunnion and provided with an opening through which said string extends from said shade-roller, said shoulders being normally engaged with one another for locking the shade 115 roller, said trunnion being movable in said bearing by said string for disengaging said shoulders from one another and unlocking the roller, substantially as and for the purpose specified.

2. A shade bracket formed of a sheet metal blank and comprising apertured flanges at its opposite ends, a trunnion-bearing between the flanged ends, and a struck up shoulder between one of the flanged ends and the trunnion-bearing and adapted to control movement of a shade-roller whose trunnion is disposed in said trunnion-bearing, one of the apertured flanges being adapted to engage with means to secure the bracket 125 to engage with means to secure the bracket 130

to its support, the other apertured flange being adapted to guide a string which actuates the shade roller.

3. A shade bracket formed of a sheet metal blank and comprising apertured flanges at its opposite ends, a trunnion-bearing between the flanged ends, and a struck up shoulder between one of the flanged ends and the trunnion-bearing and adapted to 5 control movement of a shade-roller whose trunnion is disposed in said trunnion-bearing, one of the apertured flanges being adapted to engage with means to secure the bracket to its support, the other apertured 10 flange being adapted to guide a string which actuates the shade roller and to receive a curtain-pole holder through one of its apertures.
4. In combination with a window shade, 15 a pair of shade-brackets, a roller rotatably supported by the shade-brackets, means including a headed fastener for securing the

shade on the roller, said fastener being normally covered by the shade, and a pawl carried by one of the shade-brackets and normally held out of coöperative relation with the headed fastener but being brought into coöperative engagement with the said fastener by the unwinding of the shade and the consequent uncovering of the headed fastener. 25

5. In a combined shade-supporting and roller-stopping device, a shade-bracket formed with a slotted ear, and a pawl formed of a blank of sheet metal and having a flange extending through the slot of said ear and a tongue struck up in the pawl flange, said tongue being yieldable to permit it to pass through the slot in said ear and effective to retain the tongue in movable engagement with the ear, for the purpose specified. 35

In testimony whereof I have hereunto set my hand.

JAMES WILLIAM TATUM.
